Primary Examiner — Katherine Glennon*Assistant Examiner* — Yuan Yuan(74) *Attorney, Agent, or Firm* — Casey H. Kempner, Siamak S. Hefazi(57) **CLAIM**

The ornamental design for a four-way net, as shown and described.

DESCRIPTION

FIG. 1 is a perspective view of a four-way net showing the claimed design;

FIG. 2 is a first side view thereof, the second, third, and fourth side views being identical to the first side view;

FIG. 3 is a top plan view thereof; and,

FIG. 4 is a bottom plan view thereof.

Broken lines in the figures show portions of the four-way net that form no part of the claimed design.
